UNITED STATES PATENT OFFICE

HOWARD L. FISCHER, OF ST. PAUL, MINNESOTA

PENCIL

Application filed October 19, 1922. Serial No. 595,606.

My invention relates to improvements in pencils and is particularly adapted to a pencil wherein a small number of parts are used to provide a lead propelling means for the marking lead so that the same can be propelled, or repelled.

It is also a feature of the invention to provide an operating means which is withdrawable from the rear of the pencil barrel in a manner to carry with it the lead holder and being provided with a frictional engaging means, of a resilient nature, which engages the barrel proper of the pencil to hold the operating member in position in the pencil against free longitudinal movement.

A feature of the invention resides in providing a tubular threaded member within the barrel, or casing of the pencil which is formed with a writing point and a shoulder for engaging against the casing or barrel of the pencil so as to hold the threaded member fixed in the barrel against the writing pressure on the marking lead.

The shoulder formed on the threaded member and the writing end are integral with the same and conform with the barrel, or casing so as to provide a writing end on the pencil of a uniform and attractive appearance so as to simulate the ordinary writing end of a sharpened pencil.

The threaded member of the pencil extends into the hollow barrel unsupported at its rear end, and a suitable means is provided for centering this free end when the pencil is in operation. This is accomplished either with the operating member or by suitable means which are brought into engagement with the barrel and the threaded tube at its rear end. It is not wholly essential that the inner free end of the center tube be secured excepting when the pencil is in use so as to cause it to operate properly. Obviously the operating member which extends axially into the barrel, from the rear end, will center the rear free end of the threaded member.

All of the features of the invention will be clearly defined and set forth in the specification and claims.

In the drawings forming a part of this specification:

Figure 1 is a longitudinal cross section of my pencil.

Figure 2 is a longitudinal cross section of my pencil with the operating member removed therefrom.

Figure 3 illustrates an alternative construction of my pencil where the different casing, or barrel is used.

Figure 4 illustrates a different form where in the center threaded tube is independent from the writing tip.

Figure 5 illustrates means for centering the rear end of the threaded tube.

Figure 6 is a detail of the threaded tube illustrated in Figure 5.

Figure 7 is a cross section on the line 7—7 of Figure 5.

Figure 8 is a cross section similar to Figure 7, illustrating a means of centering the threaded member in the pencil.

Figure 9 is a perspective view of the centering member used in Figure 8.

In the drawings the pencil A is illustrated with a composition barrel, or casing member 10 formed of wood, rubber, ivory, or a fibre material, which is non-metallic.

The casing 10 is formed with a forward conical portion 11 having the same taper as that of the writing end of the pencil and is provided in the rear portion thereof with an enlarged chamber 12.

A tubular threaded member 13 is provided with threads 14 extending into the forward end 11 through the opening 15 in the casing 10, so as to frictionally engage the member 13 and hold it against free disengagement from the casing. The forward end of the threaded member 13 is formed conical to provide a writing tip 16 which is provided with an opening 17 through the apex for the marking lead 18 held in writing position in the pencil.

A shoulder 19 is formed on the writing tip 16, which engages with the forward edge of the casing 10 in a manner to hold the threaded member in the pencil so that the writing pressure on the lead will be transmitted from the shoulder to the forward edge of the casing and thus provide a construction wherein only a minimum friction is required through

the opening 15 to hold the threaded member in the barrel 10.

The threaded tubular member 13 extends into the chamber 12 of the casing 10 in a manner to provide a circular magazine chamber 20 for extra marking leads 18.

An operating member 21, which carries the lead carrier 22, extends axially within the threaded member 13 and is provided with 10 an operating head 23 which carries an eraser 24 with a cap 25 covering the eraser and forming a finger engaging end for operating the member 21. When the cap 25 is removed the head 23 proper can be engaged and operated to rotate the member 21 and thereby cause the lead carrier 22 to be rotated over the threads 14 and propel or repel the marking lead 18.

The head 23 is formed with a shank 26 20 which is provided with an annular recess 27, in which a spring friction sleeve 28 is held. The spring sleeve 28 is adapted to engage directly with the inner surface of the barrel, or casing 10 and to provide a locking means 25 for holding the operating member 21 against free longitudinal movement, but in a manner so that it can be freely rotated to operate the writing lead in writing position.

The shank 26 is formed with a recess 29 into 30 which the free end 30 of the threaded member 13 is adapted to extend in a manner so as to center the end 30 in relation to the casing 10 and operating head 23. This means of centering the threaded member at its rear free 35 end eliminates any extra parts which might be required to hold the threaded member 13 centrally within the casing, while the forward end of the same is held within the bore, or opening 15. In this manner the threaded 40 member is held centrally throughout its length within the barrel. The recess 29 is formed with a bevelled edge so as to cause it to freely and readily engage the end 30 of the threaded member.

45 In Figure 3 a metallic, or thin wall casing 10' is provided, the forward end of which is swaged to form the writing tip and the threaded member 13' is fixed within the barrel by means of a collar 31 which is fixed to the threaded member 13' and which frictionally engages the barrel to hold the threaded member within the same. The forward end of the threaded member 13' engages the inner conical surface of the writing tip.

55 In this construction the rear end of the threaded member 13' is held in exactly the same manner as illustrated in Figure 1, extending within the recess 29 of the shank 26, while the frictional spring sleeve 28 engages 60 the casing to hold the operating member 21 within the barrel against free longitudinal movement.

The spring sleeve 28 holds the operating member against longitudinal movement when 65 in operation in the pencil to propel, or repel

the marking lead and permits the same to be withdrawn from the casing and threaded member so as to insert a new marking lead in the socket of the lead carrier 22. When the operating member 21 is removed from 70 the casing the marking leads in the magazine chamber 20 can be freely withdrawn.

The construction illustrated in Figure 1 and Figure 2 permits the threaded member 13 to be withdrawn and replaced by a new 75 similar member by engaging the writing tip 16 and withdrawing the same from the opening 15.

In the drawings, Figures 5, 6 and 7 illustrate spacing members 35, which are formed 80 in the inner end of the member 13 and adapted to engage the casing 10 within the chamber 12 to center the rear end 30 of the threaded member 13. In this construction it is not necessary to provide a recess 29 within the 85 shank 26.

In Figure 4 a writing tip 36 is provided with a threaded end 37 which is adapted to engage within the forward end of the barrel 10 to hold the tip 36 independent of the 90 threaded member 38 of the pencil. In this construction the tip 36 may be provided with a shell 39 of precious metal to cover the outer surface of the tip. In this construction the threaded member 38 is formed with an annular shoulder 40 on its forward end which engages against a complementary similar shoulder formed near the forward end of the opening 15 to hold the threaded member 38 against backward movement in the pencil 95 casing. When the tip 36 is removed from the casing the threaded member 38 can be forced out of the opening 15 to remove it from the casing, thus the threaded end of the tip is adapted to engage the shoulder 40 and 100 assist in holding the threaded member 38 in the barrel in this construction.

The threaded tube 38 is formed with a shoulder 40 on its forward end and the rear end is slit as illustrated in Figure 6 so that 110 after the threaded member 38 has been inserted through the opening 15 in the composition barrel and the tip 36 is screwed into the threaded portion 37 the spacing members 35 are bent up so as to project radially from 115 the tube 38 and engage the inner surface of the barrel to form spacing members 35. The member 38 is formed of comparatively soft material and the members 35 can be easily engaged and bent in place to form a separate piece at the rear end of the tube 38, and when this member 38 is removed the tip 36 is first removed and then the tube 38 is pushed forward by engaging it from the rear end after the members 35 have been bent down or by 120 forcing them through the opening 15 which will cause them to bend sufficiently to allow the tube to be withdrawn through the passageway 15.

In Figures 8 and 9 a corrugated spacing 130

member 42 is used to engage the rear end of the threaded member 13 to center the same within the casing 10. These figures illustrate another manner in which the rear end of the threaded member can be held central within the casing.

It is essential in making up a pencil to provide a construction which is simple and is composed of a very small number of parts. With this in mind I have endeavored to illustrate in Figures 1 and 2 a most simple construction, where a composition barrel can be used for the casing of a pencil. The parts are easily manufactured and readily assembled so as to provide a pencil with a non-metallic barrel and yet containing a practical lead propelling mechanism so that the marking lead will be held firmly in writing position and can be easily withdrawn or forced 20 into the pencil casing to protect the same. The lead carrier 22 is provided with all of the features of my Patent No. 1,870,420 issued on March 1st, 1921. The frictional engagement of the sleeve 28 under spring tension, 25 with the casing of a composition barrel, provides a very efficient means for holding the operating member of the pencil in the casing.

The formation of the threaded member of my pencil is an important feature of the invention, as illustrated in Figures 1 and 2, as it provides an extremely simple, inexpensive construction; the writing tip is formed as an integral part with the threaded member, providing an annular shoulder to hold it in position in the casing. It will be readily apparent that these features combine together to make up a pencil of a very desirable nature.

I claim:

44. 1. A pencil having a composition non-metallic casing, a tubular threaded member having a writing tip formed on the forward end thereof, said threaded member extending into said casing, an operating member and means associated with said operating member adapted to center the free end of said threaded member within said casing when said operating member is in position within said casing.
45. 2. A pencil including, a non-metallic casing, a threaded member extended within and supported on its forward end by said casing in a manner to project the rear end of said threaded tube within said casing to form a circular chamber thereabout for extra marking leads, a writing tip associated with the forward end of said threaded member and a lead operating means adapted to enter the rear of said casing and to center the free rear end of said threaded member.
46. 3. A pencil including, a casing, a chamber formed in said casing, a threaded member having an integral writing tip extending into said casing with its front end supported therein and the rear end unsupported by the

walls of said chamber and a lead propelling member having means for supporting the rear end of said threaded member.

4. A pencil including a casing, a threaded member insertable from the writing end of 70 said casing having a writing tip formed thereon, a lead operating member insertable from the rear of said casing, and means adapted to hold said operating member rotatable within said casing and against free 75 longitudinal movement therein.

5. A pencil having a casing, a lead propelling means including a threaded member held within the barrel, a lead carrying operating member, an operating closure head carried by said operating member and frictional means carried by said head adapted to engage said pencil casing and to remain stationary while the operating head and member are rotated in operation of said pencil. 80

6. A pencil comprising a composition barrel, a threaded member having a writing tip formed thereon adapted to be removably held in said barrel and a lead carrying operating member removably held in the rear end of 90 said pencil adapted to cooperate with and hold said threaded member centrally within the rear end of said barrel.

7. A pencil including, a composition barrel, a threaded member adapted to be removably held within said barrel, a writing tip on the forward end of said threaded member, a lead carrying operating member adapted to coact with said threaded member in a manner to operate the marking lead therein, 95 a closure operating head on said operating member and a spring sleeve carried by said closure head adapted to engage said composition barrel to frictionally hold said operating member against free longitudinal movement, 100 said operating head being removable from said pencil.

8. In a pencil comprising a barrel, an internally threaded tube spaced from and fixed axially therein, a longitudinally slotted tube 110 rotatably carried in the threaded tube, a plunger in the slotted tube having a follower which projects through the slot for engagement with the threads of the other tube and a head fixed to one end of the slotted tube telescopically engaged with one end of the barrel, whereby the slotted tube may be rotated in the barrel by means of said head or may be withdrawn with its head and plunger as a 115 unit.

9. In a pencil comprising a barrel and a removable head thereon having a lead-propelling mechanism fixedly attached to said head, an eraser pocketed in the head and an opening accessible from the same side of the head 125 to which the propelling mechanism is secured to permit the insertion of means for ejecting the eraser from the head.

10. In a pencil comprising a barrel, a removable head thereon having lead-propelling 130

mechanism attached to said head, said mechanism co-operating with a threaded tube axially fixed in and spaced from said barrel, whereby to define an annular spare lead chamber thereabout.

5 11. In a pencil comprising a barrel, a removable head thereon having lead propelling mechanism attached to said head, said mechanism having engagement with a threaded tube axially fixed in and spaced from said barrel, whereby to define an annular spare lead chamber thereabout extending the length of the barrel.

10 12. In a pencil comprising a barrel, an internally threaded tube spaced from and fixed axially therein whereby to define an annular chamber about said tube, a longitudinally slotted tube rotatably carried in the threaded tube, a plunger in the slotted tube having a 15 follower which projects through the slot for engagement with the threads of the other tube, and a head fixed to one end of the slotted tube and removably engaged with one 20 end of the barrel so that the slotted tube with 25 its head and plunger may be withdrawn as a unit from said barrel, said chamber being accessible by the removal of the slotted tube from the barrel.

30 13. In a mechanical pencil having a barrel and a tapered tip, an internally threaded tube secured in said barrel in spaced relation to define an annular chamber about the tube, and extending into the tip, and mechanism co-operating with the tube for feeding a lead 35 through the tip.

HOWARD L. FISCHER.
